UNITED STATES PATENT OFFICE.

LLOYD JONES, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

MANIPULATOR.

1,418,932.

Specification of Letters Patent. Patented June 6, 1922.

Application filed November 24, 1920. Serial No. 426,203.

To all whom it may concern:

Be it known that I, LLOYD JONES, a citizen of the United States, residing at Pittsburgh, in the county of Allegheny and State of Pennsylvania, have invented a new and useful Improvement in Manipulators, of which the following is a full, clear, and exact description.

My invention relates to manipulators and more particularly to manipulators of the "stake" type, and has its best field of application to rolling mills which are provided with lifting tables that are pivoted at or near the end away from the rolls.

With manipulators of the "stake" type as hertofore installed, it is not possible to effect an equal movement of the ends of bars or other material under operation, although such movement is essential. This is especially difficult if such material is relatively long. This defect was due to the fact that the vertical movement of a pivoted table varies from a maximum at the rolls to zero at the pivot.

My invention overcomes this defect by providing means for causing substantially the same relative movement between the table and the manipulating elements near the pivotal point of the table as that between the table and the elements near the rolls. By such an arrangement many advantages are secured and will be appreciated as this description proceeds.

My invention and its operation will be better understood by reference to the accompanying drawings forming a part thereof and in which—

Figure 1 is an elevation of a three-high rolling mill with my invention applied thereto;

Figure 2 is a fragmentary view showing the relation of the parts;

Figure 3 is a detail fragmentary view showing the relation of the rollers on the roll table to the stakes;

Figure 4 is a view similar to Figure 3 showing another relative position of the parts; and

Figure 5 is a plan view partly in section of the parts for increasing the relative movement between the manipulating elements and the table.

In the drawings, 1 is a three-high rolling mill of the ordinary construction having rolls 2, 3 and 4. The details of construc-

tion of the rolling mill form no part of my invention and therefore will not be described. The mill rests on the customary base 5. Placed at the side of the mill is a tilting table 7 of any desired construction 60 having thereon a plurality of rollers 8 for purposes well understood. The table 7 is pivoted at 9. The table is oscillated around the pivot 9 by a mechanism comprising a hydraulic or other motor 10, a connecting 65 rod 11 connecting with one end 12 of the bell crank, which is journalled at 13. The other end 14 of the bell crank is pivotally connected with a link 15 which is pivoted at 16 to the underside of the table 7. The 70 table 7 is moved from the full line position in Figure 1, to the position indicated in dotted lines, by the motor mechanism just described. Positioned along the table 7 are stands 17 and 18. These stands are pivoted 75 at 19 and 20, respectively, to the base of the machine, or to any other fixed point. Guides 21 are mounted on the table 7 and provided with openings through which the manipulating elements 22 and 23 pass. The stands 80 17 and 18 are provided with a plurality of sockets 24 into which the lower ends of the elements 22 and 23 fit. These elements may be moved from one socket to the other to meet the requirements of any particular case. 85

Arranged near the pivoted end of the table 7 is a mechanism for increasing the relative movement between the table and the manipulating element 25. This mechanism comprises a link 26 pivoted at one end at 27 90 and at the other end at 28 to an arm 29 which is connected with a shaft 30 suitably journalled in blocks 31. Connected to the shaft 30 are two arms 32 which are pivotally connected at 33 to a stand 34 of the same 95 general construction as the stands 17 and 18. The stand 34 carries the element 25 which extends through an opening in the guide 35 fastened to the table 7. The relative length of the arms 29 and 32 is such

that the relative movement between the element 25 and the table 7 is substantially equal to the relative movement between the elements 22 and 23 and the table, and by reason of this mechanism the material under 105 treatment is subject to the same manipulation at the point where it engages the element 25 as it is at the points where it is engaged by the elements 22 and 23.

The operation of my device is as follows:— 110

Material coming through the rolls 2 and 3 would be received on the tilting table which at that time would be in the position so that the rollers 8 occupy the position indicated in 5 dotted lines in Figure 1. That is to say, the table 7 would be raised so that the material 36 would rest on the rollers in a horizontal position because of the fact that the rollers are above the ends of the manipulating elements. As soon as the material passes 10 through the rollers, the table 7 is tilted around its pivot to the position shown in full lines in Figure 1. During the latter operation the rollers 8 are lowered, whereas 15 the elements 22 and 23 remain stationary and the element 25 is given a relative motion equivalent to the relative motion between the table and the elements 22 and 23. During this movement, the material slides 20 down the inclined face of the elements to the position shown in full lines in Figure 4 and in so doing is turned 90 degrees and is moved to the left, a distance depending upon the incline of the elements as shown in Figures 3 and 4. The incline, as shown in Figure 2, is sufficient to bring the material from 25 the pass in which it is indicated by the dotted lines 37, to the first groove at the left of the rolls. The material having been moved 30 sidewise to the position indicated in Figure 4, and the table having been lowered to the position shown in Figure 1, the material is ready to pass through between the rolls 3 and 4 to the other side of the machine, which 35 may be equipped with table and manipulating elements similar to that illustrated in Figure 1.

My invention has the advantage that the material is automatically kept in a position 40 substantially perpendicular to the axis of the rolls on a machine in which the tilting table is pivoted at one end and has a movement varying in amount from the point near the rolls to that near the pivotal point and by 45 reason of which construction any length of material may be used and, also, the material may be moved from one pass to the other and turned at the same time. Furthermore the device is simple and in its 50 preferred form all the relative movement between the table and elements is produced by the movement of the table itself.

Other advantages will be apparent to those skilled in the art from a reading of the 55 foregoing description.

While I have described my invention as applied to a particular machine and have shown one embodiment thereof and described the same in great detail, I wish it 60 to be understood that I do not wish it to be limited to the exact details shown and described.

I claim:

1. In a manipulator, the combination of a 65 feed table upon which the material under

treatment is placed, said table being pivoted near one of its ends, means for raising and lowering the free end of the table, a plurality of manipulating elements arranged at different points along said table and means whereby a substantially equal relative vertical movement is produced between said table and all of said manipulating elements for turning and sliding the material under treatment preparatory to the next operation, 75 substantially as described.

2. In a manipulator, the combination of a feed table upon which the material under treatment is placed, said table being pivoted near one of its ends, stationary manipulating elements near the free end of said table whereby the movement of said table is a definite amount relative to said elements, manipulating elements near the pivotal point of said table and means for actuating said elements whereby the relative movement between said last mentioned elements and said table is substantially the same as the movement between said first mentioned elements and said table, and means for moving said 90 table around said pivot, substantially as described.

3. In a manipulator, the combination of a feed table upon which the material under treatment is placed, said table being pivoted 95 near one of its ends, stationary manipulating elements near the free end of said table whereby the movement of said table is a definite amount relative to said elements, manipulating elements near the pivotal point of said table and means for actuating said last mentioned elements by said table whereby the relative movement between said last mentioned elements and said table is substantially the same as the movement between said first mentioned elements and said table, and means for moving said 105 table around said pivotal point, substantially as described.

4. In a manipulator, the combination of a feed table pivoted near one end, manipulating elements associated with said table at different points along its length, means for oscillating said table around said pivot and producing a relative vertical movement between said table and said elements, and means connecting some of said elements to said table whereby the relative movement between said table and all of said elements is substantially equal, substantially as described.

5. In a manipulator, the combination of a feed table pivoted near one end, manipulating elements independent of said table, and a manipulating element actuated by the 125 table, substantially as described.

6. In a manipulator, the combination of a feed table pivoted near one end, manipulating elements independent of said table, and a manipulating element actuated by 130

a lever mechanism connected to the table, substantially as described.

7. In a manipulator, the combination of a feed table pivoted near one end, manipulating elements along said table at different distances from the pivotal point thereof, and means whereby the relative vertical movement between the table and all the elements is substantially the same regardless 10 of the distance of the elements from the pivotal point of the table, substantially as described.

8. In a manipulator, the combination of a pivoted roll table, manipulating elements 15 independent of said table, and a manipulating element actuated by said table whereby the relative movement between said last mentioned element and the table is substantially equal to the relative movement between the table and the independent 20 manipulating elements, substantially as described.

9. In a manipulator, the combination of a pivoted roll table, manipulating elements 25 along said table and at different distances

from the pivotal point thereof and means operated by the table whereby the vertical movement of the table with respect to each of the elements is substantially the same and means for oscillating said table around 30 said pivot, substantially as described.

10. In a manipulator, the combination of a pivoted roll table, a manipulating element independent of said table and a manipulating element connected to said table by lever 35 mechanism to equalize the relative movement between the table and said manipulating elements, substantially as described.

11. In a manipulator, the combination of a pivoted table, manipulating elements in- 40 dependent of said table and manipulating elements actuated by said table and a speed changing device operatively connecting said last mentioned elements to said table, whereby the relative movement between the table 45 and all of said elements is substantially the same, substantially as described.

In testimony whereof, I have hereunto set my hand.

LLOYD JONES.
